GEORGE PENRICE FARMER, OF BROOKLYN, NEW YORK, ASSIGNOR TO E. C. PRATT, BROTHER & CO., OF NEW YORK CITY.

Design No. 4,842, dated April 25, 1871.

DESIGN FOR A SHOW-CASE FOR NEEDLE PACKAGES.

The Schedule referred to in these Letters Patent and making part of the same.

I, GEORGE PENRICE FARMER, of Brooklyn, county of Kings, State of New York, have invented or produced a Design for a Show-Case for Needle Packages, of which the following is a specification.

The figure in the accompanying drawing is a plan view of my show-case for needle packages, the said case consisting of a shallow box, to which may be hinged a glazed lid.

The box is separated into three main compartments, D, D', and E, by inclined partitions *a a*, and the compartments D D' are separated by partitions *b b* into recesses of different sizes, for the reception of different-sized needle packages.

The compartment E is separated by radial partitions *d d* into several narrower compartments, and on each side of each of the latter are small studs *e* for

retaining needle packages of different sizes in their proper position in the case.

Below the box there may, if desired, be drawers for containing spools, &c.; such drawers, however, form no part of my present design.

Claim.

The design for a partitioned case, substantially as described and as illustrated in and by the accompanying drawing.

In testimony whereof I have signed my name to this specification in the presence of two subscribing witnesses.

Witnesses:

Wm. R. HIND,
ALFRED YOUNGMAN.

G. P. FARMER.
